UNITED STATES PATENT OFFICE

116,951

DESIGN FOR A CRANKSHAFT LATHE

William F. Groene and Walter R. Meyer, Cincinnati, Ohio, assignors to The R. K. Le Blond Machine Tool Company, Cincinnati, Ohio, a corporation of Delaware

Application September 23, 1938, Serial No. 80,067

Term of patent 14 years

To all whom it may concern:

Be it known that we, William F. Groene and Walter R. Meyer, citizens of the United States and residents of Cincinnati, in the county of Hamilton and State of Ohio, have invented a new, original, and ornamental Design for a Crankshaft Lathe, of which the following is a specification, reference being had to the accompanying drawings, forming part thereof.

Figure I is a perspective view of the front and right hand side of a crankshaft lathe showing our new design.

Figure II is a perspective view of the front and left hand side of the crankshaft lathe shown in Figure I.

Figure III is a front elevation of the crankshaft lathe.

Figure IV is a right hand end elevation of the crankshaft lathe.

We claim:

The ornamental design for a crankshaft lathe, substantially as shown.

WILLIAM F. GROENE.
WALTER R. MEYER.
